United States Patent Office.

W. STORER HOW, OF CINCINNATI, OHIO.

Letters Patent No. 77,378, dated April 28, 1868; antedated April 22, 1868.

IMPROVEMENT IN VIALS.

The Schedule referred to in these Letters Patent and making part of the same.

TO WHOM IT MAY CONCERN:

Be it known that I, W. Storer How, of Cincinnati, Hamilton county, State of Ohio, have invented certain new and useful Improvements in Vials; and do hereby declare the following to be a full, clear, and exact description thereof, reference being had to the accompanying drawings, making part of this specification.

In administering medicines, it is a very common practice to prescribe a certain number of drops for a dose, and it is a well-known fact that it is almost an impossibility to regulate the flow from an ordinary vial, so as to ascertain the exact quantity which is being delivered, the liquid being more liable to flow in a stream than to issue in drops, as desired.

My improvement is designed to overcome this difficulty, and my invention consists in providing the necks of vials with one or more small apertures, which are closed when the cork or stopple is inserted, and which are capable of being opened, in whole or part, by the partial withdrawal of the stopple, so as to allow the fluid to escape drop by drop.

In the accompanying drawing—

Figure 1 is a perspective view of a vial, embodying my improvements.

Figure 2 is an axial section of the same, the stopple being partially withdrawn, and the vial inclined, so as to permit the escape of the contents; and

Figure 3 represents a modification of my invention.

A represents a bottle, jar, or vial, having the customary neck B, which is closed by a cork, or other suitable stopple, C. Projecting from the neck B are two small bosses or nipples, D D', having apertures, d d', which communicate with the interior of the vial, and these nipples are placed diametrically opposite to one another, in order that the air may enter at one while the fluid is escaping at the other.

The nipples should be sufficiently near the outer end of the neck to permit of the cork completely cutting off all communication between the apertures d and the contents of the vial, when the said cork is driven home in the neck.

As soon as the vial is inclined, and the cork partially withdrawn, the fluid will begin to issue, and, by withdrawing the cork a greater or less distance, the size of the ventage may be increased or diminished, the cork acting as a valve or gate to graduate the flow. The fluid issues from the vial in well-defined drops, and a sufficient length of time ensues between the consecutive drops to permit of their being counted with perfect accuracy.

The form represented in figs. 1 and 2 has been selected as the preferred type, because it is easily manufactured, and because it presents a symmetrical appearance, but the modified form, as seen in fig. 3, will be found equally as effective and convenient for use.

In this form of my invention the two nipples are omitted, and an elongated projection, E, having a slot, e, is substituted for them. This slot occupies a position at right angles to the axis of the neck, but it may be parallel therewith, or it may even be inclined, so as to describe a part of a helical curve around the outside of said neck.

In using this form of vial, it is held in such a position as to allow the fluid to escape at one end of the slot, while the proper quantity of air is entering at the other.

Vials constructed as herein described will not only be useful for administering medicines, but they will also be a valuable addition to the chemist's laboratory, as they will enable him to measure out a definite quantity of liquid of any kind without bringing it in contact with any other vessel.

I claim herein as new, and of my invention—

Providing the neck of a bottle, vial, or jar with one or more apertures, d d', which are so located as to be closed when the cork or stopple is completely inserted, and to be opened when the said stopple is partially withdrawn, as and for the purpose herein described and set forth.

In testimony of which invention, I hereunto set my hand.

W. STORER HOW.
